UNITED STATES PATENT OFFICE

JOHN H. SHAW, OF NEW HAVEN, CONNECTICUT, ASSIGNOR TO SARGENT & COMPANY, OF NEW HAVEN, CONNECTICUT

LOCK

Application filed March 7, 1929. Serial No. 344,975.

My invention relates to locks and more especially to locks in which a dead bolt is protractable from the outside of the room by a cylinder lock mechanism and is protractable from the inside of the room by a thumb turn or the like.

One of the primary objects of the invention is to provide a simple, inexpensive and efficient lock of the above character.

Another object of the invention is to provide an improved form of lock having a dead bolt and latch bolt in which a change key when inserted from the outside and turned will retract the latch bolt without, however, having any effect on the dead bolt, and wherein an emergency key, on the other hand, will operate the dead bolt as well as the latch bolt.

In a more specific aspect, the invention relates to improvements in that form of lock mechanism shown in the patent to Voight, No. 1,271,632, July 9, 1918. In this patent there is shown a cylinder lock mechanism having two rollbacks and a number of pin tumblers controlling the operation of the rollbacks, each of the pin tumblers being provided with two breaks or shears, one set of breaks or shears being brought into alignment by a change key in order to operate one rollback, while the other set of breaks or shears may be brought into alignment by an emergency key to operate the other rollback. As distinct from the mechanism shown in the Voight patent, it is herein proposed to provide a cylinder lock mechanism or the like provided with pin tumblers in which but a single set of breaks or shears is necessary and a single rollback is provided, which may be operated by either a change key or an emergency key. The rollback of the present invention is provided with an element which is inoperative when the rollback is actuated by a change key and which becomes operative only when the rollback is operated by an emergency key.

To these and other ends, the invention consists in the novel features and combination of parts to be hereinafter described and claimed.

In the drawings,

Fig. 1 is an elevation of a lock mechanism embodying my improvements, with the cap

plate removed, showing the dead bolt in normal retracted position;

Fig. 2 is a view of the upper part of the lock showing the dead bolt in protracted position;

Fig. 3 is a sectional view along lines 3—3 of Fig. 1;

Fig. 4 is a sectional view along line 4—4 of Fig. 2, and showing a change key received in the cylinder lock mechanism;

Fig. 5 is a view similar to Fig. 4, but showing an emergency key received in the cylinder lock mechanism;

Fig. 6 is a fragmentary view, showing the operative parts of the latch retracting mechanism; and

Fig. 7 is a sectional view along line 7—7 of Fig. 3.

Referring to the drawings in which I have illustrated my invention by showing a preferred embodiment of the same, the reference numeral 10 indicates, in general, a lock mechanism which is, except for certain improvements to be hereinafter pointed out, quite similar to that shown in the Voight patent referred to, and which is provided with a usual mortise case 11 and face plate 12, by means of which it may be mounted in a door or the like. In an upper part of the lock case

11, a dead bolt 13 is located, while in the lower part of the lock case 11 a latch 14 is provided. The latch bolt 14 may be retracted from the inside of the door by the usual knob spindle acting on a hub 15 to draw back a retracting shoe or yoke 16, having an arm 17, engaging the crosshead 18 on latch stem 19, latch 14 being urged into normal protracted position by means of coiled spring 20 mounted on stem 19 and having one end bearing against the head of the latch bolt, while the opposite end bears against a stud 21 on lock case 11.

In the upper part of the lock case a cylinder lock 22 is screwed in at the outer side in the usual manner, and this cylinder lock through connections, to be hereinafter described, is adapted to actuate a latch retracting lever 23, pivoted on its upper end to lock case 11, as at 24, and having its lower end in engagement with the crosshead 18 on latch stem 19.

The dead bolt 13 has a flat shank 25, pro-

vided with talons 26 and 27, adjacent cylinder lock 22 and a cut-out portion 29 in the upper part of the shank which receives the fence or stem 30, which is cast on the back of the case. 5 This fence guides the bolt for reciprocating movement and it is also guided in a suitable manner at the lower part of the bolt shank. Below the talons, the bolt has a cut-out portion 31 for the reception of a thumb turn hub 10 32, which is journaled between the back and cap plate of the lock case 11. In the lower part of the cut-out portion 31 a gate 33 is formed, which cooperates with a wing 34 on the thumb turn hub. This gate 33 is provided with beveled or inclined surfaces to cooperate in an obvious manner with the extreme edge of the wing 34 to deadlock the bolt in protracted position and retracted position, respectively, and between the beveled or inclined surfaces a small notch is provided to receive the edge of the wing as the latter is moved through a quarter turn for protracting or retracting the bolt.

The bolt is provided with a tumbler 35 pivoted on a post 36 at the forward part of the bolt shank, so as to be carried by the bolt, and having a projection 37 extending between the talons 26 and 27 into cooperation with the cylinder lock, as hereinafter described. 25 30 This tumbler is provided intermediate its ends with a lug 38 to cooperate with the fence 30 in locking the bolt either in the retracted position or the protracted position. Below the tumbler 35 and pivoted to the lock case is 35 a second tumbler 39 which cooperates with the thumb turn hub in deadlocking the dead bolt. This tumbler is pivoted on a post 40 and has a spring 41, reacting against a lug 42. The main part of tumbler 39 overlies the 40 lower portion of the dead bolt shank and at its upper part is provided with notches which converge toward and meet each other near the upper edge of the tumbler.

One of these notches is indicated at 43 and 45 the other at 44, and the spring exerts an upward thrust on the tumbler so as to tend to keep it firmly seated against the thumb turn hub with one or the other of the notches 43 and 44 engaging the wing 34. The tumbler 50 by being provided with these notches exerts such an upward thrust on the wing 34 as to hold it in cooperation with one or the other of the inclined surfaces of the gate 33, so that the bolt will be securely deadlocked 55 either in retracted position or protracted position and cannot be moved out of this position except by actuation of the thumb turn or key mechanism.

The spring action of the lower tumbler 39 60 is imparted to the upper tumbler 35 by means of a tumbler connector 45 having upper and lower pins 46 and 47 projecting rearwardly therefrom, the pin 47 entering a slot 48 in tumbler 35, while the lower pin 46 enters a 65 small hole in tumbler 39. The slot 48 per-

mits the bolt to be shifted without disturbing the connection of the upper movable tumbler with the lower fixed tumbler, as will be understood. The upper edge of the connecting plate is notched to fit around the fence 30 70 which guides the tumbler connector 45 in its vertical movement as the tumbler 39 moves about pivot 40.

The cylinder lock 22 comprises the usual key plug 49 controlled by sectional pin tumblers 50, key plug 49 having mounted on an inner end thereof a rollback 51 having secured thereto a spacer 52 and an end cap 53. Spacer 52 is provided with a radially directed slot 54 for the reception of the shank 80 55 of a movable abutment 56, abutment 56 being urged outwardly on rollback 51 by means of spring 57 received within a slot in the abutment shank and having an inner end bearing against screw 58 which passes 85 through the slot and into the rollback 51.

Screws 59 pass through cap 53 and spacer 52 to secure these elements to rollback 51 and thus hold the abutment and its shank against movement on rollback 51 except in a radial direction in slot 54, the outward movement of the abutment being limited by screw 58.

The latch retracting lever 23 may be actuated from the cylinder lock by means of a lever 60 pivoted on the dead bolt shank, as at 61, and having a free end 62 adapted to extend into cooperation with the upper edge of the lever 23 so that by depressing the lever 60 the lever 23 may be actuated to retract the latch. For this purpose, the lever 60 is provided intermediate its ends and in proximity to the cylinder lock with a comparatively deep operating projection 63 close to and having portions in substantial alignment with the rollback 51 and abutment 56. It will be observed, however, that the operating projection 37 on tumbler 35, while disposed in the plane of the abutment 56, is not located in the plane of the rollback 51, so that the latter will not actuate said tumbler.

The operation of the lock is as follows: Fig. 1 shows the parts in their normal position. When the guest enters the room he may insert a suitable key in the cylinder lock which will bring their breaks in the pin tumblers into alignment with the surface of the key plug, whereupon the latter may be rotated to bring the rollback 51 into engagement with lever 60 to retract the latch 14, whereupon the door may be opened and the guest may enter. When the guest is within the room and desires to lock the door from the inside, the thumb turn is actuated to advance the dead bolt, thus moving the dead bolt into the position shown in Fig. 2. In this position the lever 60, which is carried on the post 61 of dead bolt 13 is moved to such a position that operation of the lock mechanism by use of the ordinary change key will have no effect thereon.

It will be noted that in this position rotation of the key plug will bring the abutment 56 into engagement with the tumbler 35, but the latter will not be actuated, owing to the fact that the abutment is free to reciprocate inwardly on the rollback, and thus clear the end of the tumbler and the talons on the dead bolt. If, however, an emergency key, such as that shown in Fig. 5, is inserted in the cylinder lock, the extended shank on the key is received under the end of the shank of the abutment 56 and holds the latter against movement in an inward direction. Rotation of the key plug 49 by means of the key will now bring the abutment 56 into contact with the projection 37 on tumbler 35 to depress the latter and to bring the lug 38 out of engagement with the fence 30, further movement of the key plug and abutment 56 bringing the latter into engagement with talon 26 to move the dead bolt inwardly into retracted position, the initial movement of the dead bolt bringing the lever 60 into position where it may be engaged by the rollback 51 to retract the latch, whereupon the door may be opened.

It will be noted that the cylinder lock is provided with pin tumblers in which there is but a single set of breaks or shears, while but 30 a single rollback is provided, this rollback, however, being capable upon insertion of an emergency key, of operating the dead bolt mechanism, whereas, upon the insertion of the ordinary or change key, the latch only 35 may be actuated.

While I have shown a preferred embodiment of my invention, it is to be understood that the same is not to be limited to all the details shown but is capable of modification 40 and variation within the spirit of the invention and the scope of the appended claims.

What I claim is:

1. A cylinder lock comprising a casing, a rotatable key plug in said casing, a rollback 45 mounted on said key plug, an element mounted on said rollback having a radially directed slot, an abutment having a stem slidably received in said slot, the stem of said abutment being provided with a radially directed slot, a fixed element passing through said last 50 named slot and into said rollback, said fixed element serving to limit movement of the stem in the slot of the slotted element, a compression spring mounted in the stem and having one of its ends in engagement with the 55 fixed element, while the other end of the spring is in engagement with the abutment and urges the latter radially outwardly, said key plug being provided with a key receiving slot and the stem being carried in the slotted element adjacent said key receiving slot, whereby it may be engaged by a key inserted in the key plug to be held outwardly 60 against the fixed element.

2. A cylinder lock comprising a casing, a

rotatable key controlled member, an abutment carried by said rotatable member and movable thereon in a radial direction, said abutment being provided with a stem having a slot, a compression spring having one end in engagement with the abutment and resiliently urging the latter outwardly on the key controlled member, relatively fixed means on the key controlled member against which the other end of said spring bears, said fixed means acting to limit the outward movement of the abutment on the member, and means whereby said abutment may be held against movement in a radial direction. 70

3. A cylinder lock comprising a casing, a rotatable key plug in said casing, a rollback mounted on said key plug, an element mounted on said rollback having a radially directed slot, an abutment having a stem slidably received in said slot, a compression spring urging said abutment radially outwardly in said slot, means for limiting the outward movement of the abutment in the slot, said key plug being provided with a key receiving slot and said abutment having a part thereof adjacent said key receiving slot, whereby it may be engaged by a key inserted in the key plug to be held against inward movement. 80

4. A cylinder lock comprising a casing, a rotatable key controlled member, an abutment or rollback connected to said member, resilient means constantly urging said abutment into operative position, and means for holding said abutment rigidly against movement away from such operative position. 90

5. A cylinder lock comprising a casing, a rotatable key controlled member, a slotted element mounted on said member, an abutment having a stem slidably received in said slot, the stem of said abutment being provided with a radially extending slot, a fixed element mounted on said member and limiting movement of the abutment in an outward direction, a spring urging said abutment against the fixed element, said abutment being normally free to move radially inwardly against the compression of said spring, and said abutment being adapted to be engaged by a key inserted in the cylinder lock to be held against inward movement away from the fixed means. 100

6. A cylinder lock comprising a casing, a rotatable key controlled member, an abutment or rollback mounted on said member, resilient means constantly urging said abutment into operative position, and means by which a key inserted into the lock may hold said abutment from moving out of such operative position. 110

7. A cylinder lock comprising a casing, a rotatable key controlled member, an abutment mounted on said member for relative movement in a radial direction, and means constantly urging the abutment outwardly into operative position, said abutment being 120

normally free to move inwardly against said urging means and said abutment having a part thereof adjacent the key receiving slot of the cylinder lock and adapted to be engaged by a key received therein to hold the abutment rigidly against inward movement.

8. A cylinder lock comprising a casing, a key controlled rotatable member, an abutment mounted on said member for movement in a radial direction, said abutment being normally freely movable radially inwardly, resilient means for urging said abutment radially outwardly, means for limiting the outward movement of said abutment, and means by which a key inserted into the lock may hold the abutment against the limiting means.

9. A cylinder lock comprising a casing, a key controlled rotatable member, an abutment or rollback having an operative connection with said member, said abutment being movable in a radial direction, resilient means for urging said abutment outwardly, means for limiting the outward movement of the abutment, and means in addition to said resilient means for holding said abutment outwardly against the limiting means, said holding means preventing inward movement of the abutment.

10. A cylinder lock comprising a casing, a rotatable key controlled member, an abutment mounted on said member for relative movement in a radial direction, means constantly urging the abutment radially outwardly, said abutment being normally free to move inwardly against said urging means and means by which a key may hold the abutment rigidly against inward movement.

11. A cylinder lock comprising a casing, a key controlled rotatable member, an abutment mounted for movement on said member, means for limiting the movement of said abutment, and means for holding the abutment rigidly against movement away from the limiting means.

45 In witness whereof, I have hereunto set my hand this 14th day of February, 1929.

JOHN H. SHAW.
